PERIODIC WAVE REPEATER

Harold A. Wheeler, Great Neck, N. Y., assignor to
Hazeltine Corporation, a corporation of Delaware

Application March 30, 1939, Serial No. 264,935

10 Claims. (Cl. 250—36)

This invention relates to improvements in periodic wave repeaters adapted to be excited by periodic pulses and, while of general utility, it is particularly useful in any saw-tooth wave generator for television apparatus having relatively long trace and relatively short retrace intervals and adapted to be synchronized by periodic pulses, being of special utility in that type of generator comprising an oscillator having a vacuum tube which is conductive during the trace intervals.

Periodic wave repeaters adapted to be excited by periodic pulses may have an undesirable characteristic, due to the fact that undesired pulses present with the desired pulses tend to affect the operation of the repeater and this is particularly true if the undesired pulses are in amplitude comparable with the desired pulses. Also, the operation of such repeaters may not be entirely satisfactory because undesired pulses of the amplitude of desired pulses tend to impair the operation of the repeater at particular points in the cycle. For instance, in a saw-tooth wave generator having relatively long trace and relatively short retrace intervals, such as is commonly used in television scanning apparatus, the synchronizing of the saw-tooth oscillator utilized may be affected by undesired pulses as well as desired pulses and, in general, this is particularly true if the vacuum tube utilized in the saw-tooth scanning oscillator is conductive during the trace interval. Also in some cases, for instance, in submultiple-frequency generators such as are commonly used in the timing chain of television transmitting apparatus, it may be desired to effect synchronization by particular ones of the pulses from a source of periodic synchronizing signals, that is, the ones of the pulses occurring at predetermined intervals, and in such cases it is particularly desirable that the apparatus be insensitive to all undesired pulses.

Various methods have been utilized in arrangements of the prior art for eliminating one or more of the above-mentioned disadvantages. For instance, it has been proposed in one system to limit the amplitude of the source of synchronizing signals so that no undesired pulses appear therein with an amplitude greater than that of desired pulses. Such arrangements are not sufficient for satisfactory operation of a saw-tooth scanning generator having an oscillator comprising a vacuum tube which is conductive during trace intervals of the system, because even a weak undesired pulse occurring during a trace interval necessarily affects the operation of the system. Also, arrangements have been pro-

posed for a generator adapted to be synchronized by an external source of pulses the purpose of which is to render the oscillator insensitive during predetermined intervals so that undesired pulses applied thereto during these intervals will not affect the operation. However, some of these arrangements are unduly complex and expensive to manufacture. Further, it is particularly desirable to provide an arrangement in which no synchronizing pulses are applied to the input circuit of the oscillator except at predetermined intervals when synchronization is desired.

It is, therefore, an object of the present invention to provide an improved periodic wave repeater adapted to be excited by periodic pulses applied thereto.

It is another object of the invention to provide a saw-tooth wave generator, having relatively long trace and relatively short retrace intervals and adapted to be synchronized by periodic pulses, comprising an oscillator having a vacuum tube which is conductive during the trace intervals but which is protected from being affected by undesired pulses in the synchronizing source over the major portion of the period of the oscillator.

It is still another object of the invention to provide a periodic wave repeater, adapted to be excited by periodic pulses, comprising an arrangement by virtue of which no exciting pulses are applied to the repeater except at predetermined intervals during which it is desired that the repeater be excited by the external source of pulses.

In accordance with the invention, a periodic wave repeater adapted to be excited by periodic synchronizing pulses comprises a vacuum tube having a pulse-responsive input circuit, a diode effectively in series in the input circuit for coupling the periodic pulses thereto, means for deriving from the vacuum tube a periodic voltage having a value at a predetermined point of each period substantially different than that over the major portion of the period, and means for applying this derived voltage as a bias to the diode with such polarity that it is biased in opposition to conductivity to a lesser degree at the predetermined point of each period than over the major portion of each period. The periodic pulses are applied to the diode with such polarity as to tend to render the diode conductive and the value of the above-mentioned derived voltage of substantially different value is such that the diode is rendered conductive if such value occurs simul-

taneously with one of the exciting pulses. The amplitude of the derived voltage, over the major portion of the period of the oscillator, however, is of such value that the diode is maintained nonconductive even in the presence of a pulse of an amplitude comparable with that of the pulses utilized to excite the periodic wave repeater.

In a preferred embodiment of the invention, the repeater comprises a saw-tooth wave oscillator for generating pulses having relatively long trace and relatively short retrace intervals and the oscillator is adapted to be synchronized by periodic pulses from a suitable source. Also in a preferred embodiment of the invention, the above-mentioned derived voltage applied as a bias to the diode is a saw-tooth voltage used as a regenerative voltage for the oscillator and, in accordance with one form of this embodiment, the vacuum tube of the oscillator is conductive during the trace intervals.

For a better understanding of the invention, together with other and further objects thereof, reference is had to the following description taken in connection with the accompanying drawing and its scope will be pointed out in the appended claims.

Fig. 1 of the drawing is a circuit diagram, partly schematic, of a complete television receiver comprising a line-frequency scanning generator embodying the invention, while Fig. 2 comprises graphs illustrating certain of the operating characteristics of the system of Fig. 1.

Referring now more particularly to the drawing, the system illustrated in Fig. 1 comprises a modulated-carrier television signal receiver of the superheterodyne type including an antenna system 10, 11 connected to a radio-frequency amplifier 12 to which are connected in cascade, in the order named, an oscillator-modulator 13, an intermediate-frequency amplifier 14, a detector 15, a video-frequency amplifier 16, and an image-reproducing device 17. A line-frequency generator 18 and field-frequency generator 19 are coupled to the output circuit of the detector 15 through a synchronizing-signal separator and processor 20, the line-frequency generator 18 being coupled to a scanning winding 21 of image-reproducing device 17 in a manner to be hereinafter fully described, and the output circuit of field-frequency generator 19 being coupled to a field-scanning winding of image-reproducing device 17 in a similar or other suitable manner. The stages or units 10-17, inclusive, 19, and 20 may all be of conventional well-known construction so that detailed illustrations and descriptions thereof are unnecessary herein.

Referring briefly, however, to the operation of the above-described system as a whole, television signals intercepted by the antenna 10, 11 are amplified in radio-frequency amplifier 12 and coupled to the oscillator-modulator 13 wherein they are converted into intermediate-frequency signals which, in turn, are selectively amplified in the intermediate-frequency amplifier 14 and delivered to detector 15. The modulation components of the signal are derived by the detector 15 and the video-frequency components thereof are supplied to the video-frequency amplifier 16 wherein they are amplified and from which they are supplied in the usual manner to a brightness-control electrode of the image-reproducing device 17. The modulation components are also supplied to the synchronizing-signal separator and processor 20, from which suitable synchronizing

signals are supplied to the control circuits of generators 18 and 19. The intensity of the scanning beam of device 17 is modulated or controlled in accordance with the video-frequency voltages impressed upon its brightness-control electrode in the usual manner. Scanning waves are generated in the line-frequency and field-frequency generators 18 and 19, respectively, which are synchronized by the output of synchronizing-signal separator and processor 20, and these waves are applied to the scanning elements of the image-reproducing device 17 to reproduce scanning fields and thereby to deflect the beam in two directions normal to each other so as to trace a rectilinear pattern on the screen and thereby to reconstruct the transmitted image.

The arrangement of the present invention is illustrated in Fig. 1 of the drawing as applied to a particular type of periodic wave repeater, specifically, a line-frequency scanning generator 18 adapted to be excited by periodic pulses which forms the subject matter of applicant's copending application Serial No. 256,033, filed February 13, 1939. Similar circuit elements of the line-frequency generator 18 of Fig. 1 and of the modification of Fig. 5 of the above-mentioned copending application have identical reference numerals. Generator 18 comprises a high-mu screen-grid vacuum tube 31 having a pulse-responsive input circuit and a low-mu reversed triode tube 32. The tubes 31 and 32 have output circuits coupled with opposite polarity to the load circuit of the system including a parallel-resonant circuit comprising a shunt capacitance 38, shown in dotted lines for the reason that it may be comprised wholly or partially of the inherent capacitance of the circuit, and the load inductance of scanning coil 21. Scanning coil 21 is coupled into the parallel-resonant circuit by means of an autotransformer comprising primary windings 39' and 40' and secondary winding 40' is used to transform the low inductance of scanning winding 21 to the higher inductance required in the output circuit of tube 31. The effective inductance of the resonant output circuit of tube 31 is thus that of the transformer primary windings 39', 40' as measured with the scanning winding 21 connected across the secondary winding 40'.

Tube 32 is essentially a wave form stabilizing device which is designed to act as a negative resistance during the trace interval, increasing the amplitude of the current in the load circuit and compensating at least partially for the resistance therein. It has no effect during the retrace intervals and particularly does not obstruct the occurrence of a half-cycle of free oscillation of the load circuit during the retrace interval. The plate electrode 22 of tube 32, conventionally used as an anode, is here used as a control electrode and is subjected to a control voltage which controls a relatively large current in the output circuit of tube 32, which is here the circuit comprising the grid 23 and cathode 29. Voltage variations in the output circuit of tube 32 during trace intervals are less than the variations of the control voltage applied to its control circuit by the variations of the load voltage of the system, which are relatively large. This is due to the fact that, while a relatively small current is required in its input circuit, a relatively large saw-tooth control voltage is required in the input circuit of tube 32 and this is obtained from the load circuit of the system by virtue of the high

peak voltage which exists across the load circuit during the retrace interval. A saw-tooth voltage is obtained for this purpose across a condenser 41 connected in series with a resistor 42 directly across the load circuit. The voltage of condenser 41 is coupled to the control electrode of tube 32 through a coupling condenser 43 and a leak resistor 64.

A bias voltage is provided for tube 31 by means of a cathode resistor 60 by-passed by condenser 61. A feed-back circuit is also provided for tube 31, designed to supply pulse and saw-tooth voltages to its input electrode and at the same time to neutralize any kickback into the source of synchronizing signals 20. This feed-back and neutralizing circuit includes windings 66 and 67 of the output transformer, transformer winding 66, resistor 73, and condenser 68 being provided to generate a saw-tooth feed-back voltage across condenser 68 in the input circuit of tube 31. Periodic synchronizing pulses from source 20 are coupled into the input circuit of vacuum tube 31 through a diode 80 and provide current pulses which are developed into voltage pulses by means of resistor 81 in the input circuit of tube 31.

Aside from the particular improvement of the circuit of Fig. 1 which forms the subject matter of the present invention, the operation of the line-frequency generator 18 is substantially as described in detail in the above-mentioned copending application and may be briefly stated as follows: Assuming that the required current of saw-tooth wave form flows through scanning inductance 21 during the trace interval, a voltage pulse of high amplitude is developed by the rapid change of current in the load inductance 21 during the retrace interval, in which both tubes 31 and 32 are maintained nonconductive, and a relatively small pulse voltage is developed during the trace interval. The desired current and voltage wave forms associated with the load circuit of the system are obtained by developing currents in tubes 31 and 32 which have saw-tooth wave forms during trace intervals, but which are reduced to zero during retrace intervals. The required energy is thus supplied to the load circuit only during trace intervals, a half-cycle of free oscillation taking place in the load circuit during each trace interval. The saw-tooth voltages developed across condensers 41 and 68 are applied to the input circuits of tubes 32 and 31, respectively, to provide the required saw-tooth current during the trace intervals, and the pulse voltages reduce their current output to zero during the retrace intervals.

Reference is made to Fig. 2 for an explanation of the operation of the present invention in the circuit of Fig. 1. The negative synchronizing pulses from source 20 produce voltage pulses on the cathode of the diode 80, as represented by curve A of Fig. 2, the initial potential of the cathode of the diode being taken as a reference value. It is seen that, as applied to the diode-cathode, these negative pulses tend to render the diode conductive. Peaks b of curve A represent pulses by which it is desired to synchronize the line-frequency generator 18, while peaks c represent undesired pulses which may, for instance, be caused by transient disturbances in the system. The derived saw-tooth voltage developed across condenser 68 by means of transformer winding 66 and resistor 73, which is a periodic voltage having a substantially different value at a predetermined point of each period than over the major portion of each period, is applied as a bias to the anode of

5 diode 80 with such polarity that diode 80 is biased in opposition to conduction to the least degree at the point of each period at which it is desired to synchronize the oscillator by means of pulses b, that is, at the above-mentioned predetermined point of each period. A suitable unidirectional bias is also applied to diode 80 from the lower part of resistor 60. This bias and saw-tooth voltage as applied across diode 80, together with the pulses from source 20, are represented by 10 curve D of Fig. 2, representing the voltage of anode relative to cathode. The amplitude of the portion of the saw-tooth bias voltage of substantially different value is such that the diode 80 is rendered conductive if such value occurs simultaneously with one of the pulses b, while the amplitude of the portion of the saw-tooth bias voltage during the major portion of the period is such that diode 80 is maintained nonconductive even in the presence of a pulse c of amplitude 15 comparable to that of the pulses b. Since the diode 80 becomes conductive only when its anode is positive with reference to its cathode, it is apparent that no pulses are passed by the diode except at the precise time when its effective bias, due to the unidirectional-bias voltage developed across resistor 60 and the derived saw-tooth bias voltage across condenser 68, is zero, that is, when it is desired to synchronize the generator 18; that is, the amplitude of the saw-tooth voltage developed across condenser 68 is of such value at the time corresponding to a pulse b as to render the diode 80 conductive, since such value occurs simultaneously with a synchronizing pulse, but its 20 value over the major portion of the period is such that the diode 80 is maintained nonconductive even in the presence of a pulse such as c of amplitude comparable to that of the desired synchronizing pulses b. When the diode 80 becomes conductive, current pulses flow from source 20 through diode 80, condenser 68, and resistor 81, and the corresponding voltage pulses developed across the impedance means comprising resistor 81 are injected into the input circuit of vacuum tube 31, that is, the circuit comprising resistor 81, condenser 68, and winding 67, the voltage 25 pulses having a magnitude sufficient to synchronize the generator.

It will be seen that, in the embodiment of the 30 invention illustrated, tube 31 is conductive during the trace intervals of the generated wave and is, therefore, susceptible to disturbances in the source of synchronizing signals during the trace interval. The arrangement of the present invention is, therefore, designed to provide a means by which any disturbances in the source 20 of an amplitude comparable with the desired synchronizing pulses are kept out of the input circuit of tube 31 during the major portion of its cycle and thereby are prevented from undesirably affecting the output current of tube 31. At the same time, a feed-back voltage of saw-tooth wave form is continuously applied to the control grid of tube 31 from condenser 68 for maintaining the proper 35 wave form of the output current of tube 31.

While there has been described what is at present considered to be the preferred embodiment of this invention, it will be obvious to those skilled in the art that various changes and modifications may be made therein without departing from the invention, and it is, therefore, aimed in the appended claims to cover all such changes and modifications as fall within the true spirit and scope of the invention.

What is claimed is:

1. A periodic wave repeater adapted to be excited by periodic synchronizing pulses comprising, a vacuum tube having a pulse-responsive input circuit, a diode effectively in series in said input circuit for coupling said pulses thereto, means for deriving from said tube a periodic voltage having a substantially different value at a predetermined point of each period than over the major portion of each period, and means for applying said derived voltage as a bias to said diode with such polarity that it is biased in opposition to conduction to a lesser degree at said predetermined point of each period than over said major portion of each period, said pulses being applied to said diode with such polarity as to tend to render said diode conductive, the amplitude of said voltage of substantially different value being such that said diode is rendered conductive if such value occurs simultaneously with one of said pulses, and the amplitude of said derived voltage during said major portion of said period being such that said diode is maintained nonconductive even in the presence of a pulse of amplitude comparable with that of said pulses. 20
2. A periodic wave generator adapted to be excited by periodic synchronizing pulses comprising, a vacuum-tube oscillator having a pulse-responsive input circuit, a diode effectively in series in said input circuit for coupling said pulses thereto to synchronize said oscillator, means for deriving from said oscillator a periodic voltage having a substantially different value at a predetermined point of each period than over the major portion of each period, and means for applying said derived voltage as a bias to said diode with such polarity that it is biased in opposition to conduction to a lesser degree at said predetermined point of each period than over the major portion of each period, said pulses being applied to said diode with such polarity as to tend to render said diode conductive, the amplitude of said voltage of substantially different value being such that said diode is rendered conductive if such value occurs simultaneously with one of said pulses, and the amplitude of said derived voltage over said major portion of said period being such that said diode is maintained nonconductive even in the presence of a pulse of amplitude comparable with that of said pulses. 30
3. A periodic wave generator adapted to be excited by periodic synchronizing pulses comprising, a vacuum-tube oscillator having a pulse-responsive input circuit and an output circuit, a diode effectively in series in said input circuit for coupling said pulses thereto to synchronize said oscillator, means for deriving from said output circuit a periodic voltage having a substantially different value at a predetermined point of each period than over the major portion of said period and for applying said voltage to said input circuit for feedback in said oscillator, and means for applying said derived voltage as a bias to said diode with such polarity that it is biased in opposition to conduction to a lesser degree at said predetermined point of each period than over said major portion of each period, said pulses being applied to said diode with such polarity as to tend to render said diode conductive, said voltage of substantially different value being such that said diode is rendered conductive if such value occurs simultaneously with one of said pulses, and the amplitude of said voltage during said major portion of said period being such that said diode is maintained nonconduc- 40
5. A saw-tooth wave generator for generating pulses having relatively long trace and relatively short retrace intervals and adapted to be synchronized by periodic synchronizing pulses comprising, a vacuum-tube oscillator having a pulse-responsive input circuit and an output circuit, a diode effectively in series in said input circuit for coupling said pulses thereto, means for deriving from said output circuit a periodic saw-tooth voltage and applying said voltage to said input circuit for feedback in said vacuum tube, and means for applying said derived voltage also as a bias to said diode with such polarity that it is biased in opposition to conduction to a substantially lesser degree at one extreme value of said saw-tooth voltage, said pulses being applied to said diode with such polarity as to tend to render said diode conductive, the amplitude of said one extreme value voltage being such that said diode is rendered conductive if such value occurs simultaneously with one of said pulses and the amplitude of said derived voltage over the major portion of said period being such that said diode is maintained nonconductive even in the presence of a pulse of an amplitude comparable with that of said pulses. 50
6. A saw-tooth wave generator for generating pulses having relatively long trace and relatively short retrace intervals and adapted to be synchronized by periodic synchronizing pulses comprising, a vacuum-tube oscillator having a pulse-responsive input circuit and an output circuit, a diode effectively in series in said input circuit for coupling said pulses thereto, means for deriving from said output circuit a periodic saw-tooth voltage having an amplitude relatively large with respect to the amplitude of said periodic pulses, means for applying said derived voltage as a bias to said diode with such polarity that it is biased in opposition to conduction to a lesser degree at one extreme value of said saw-tooth voltage, means for supplying to said diode a unidirectional-bias voltage of such polarity and magnitude as to reduce the effective bias due to said unidirectional bias and said derived voltage approximately to zero at said one extreme value of said saw-tooth voltage, said pulses being applied to said diode with such polarity as to tend to render said diode conductive. 60
7. A saw-tooth current wave generator having relatively long trace and relatively short retrace intervals and adapted to be synchronized by periodic synchronizing pulses comprising, a vacuum-tube oscillator having a pulse-responsive input circuit, said vacuum tube being conductive during said trace intervals and, therefore, susceptible to undesired disturbing pulses during said trace intervals, a diode effectively in series in said input circuit for coupling said pulses thereto, means for deriving from said tube a periodic voltage having a substantially different value at a predetermined point of each period than over the major portion of said period, and means for applying said derived voltage as a bias to said diode with such polarity that it is biased in opposition to conduction thereof to a lesser degree at said predetermined point of each period than over said major portion of each period, said pulses being applied to said diode with such polarity as to tend to render said diode conductive, the amplitude of said voltage of substantially different value being such that said diode is rendered conductive if such value occurs simultaneously with that of said pulses. 70
8. A saw-tooth current wave generator having relatively long trace and relatively short retrace intervals and adapted to be synchronized by periodic synchronizing pulses comprising, a vacuum-tube oscillator having a pulse-responsive input circuit, said vacuum tube being conductive during said trace intervals and, therefore, susceptible to undesired disturbing pulses during said trace intervals, a diode effectively in series in said input circuit for coupling said pulses thereto, means for deriving from said tube a periodic voltage having a substantially different value at a predetermined point of each period than over the major portion of said period, and means for applying said derived voltage as a bias to said diode with such polarity that it is biased in opposition to conduction to a lesser degree at said predetermined point of each period than over said major portion of each period, said pulses being applied to said diode with such polarity as to tend to render said diode conductive, the amplitude of said voltage of substantially different value being such that said diode is rendered conductive if such value occurs simultaneously with that of said pulses. 75

neously with one of said pulses, and the amplitude of said derived voltage over said major portion of said period being such that said diode is maintained nonconductive even in the presence of an undesired pulse of amplitude comparable with that of said pulses.

7. A saw-tooth wave generator adapted to be synchronized by periodic synchronizing pulses comprising, a vacuum-tube oscillator having a pulse-responsive input circuit, a diode effectively in series in said input circuit for coupling said pulses thereto, a regenerative circuit for said vacuum tube comprising a condenser in said input circuit and a resistor for deriving across said condenser a saw-tooth voltage, and means for applying said derived voltage as a bias to said diode with such polarity that it is biased in opposition to conduction to a substantially lesser degree at one extreme value thereof, said pulse being applied to said diode with such polarity as to tend to render said diode conductive, the amplitude of said voltage of said one extreme value being such that said diode is rendered conductive if such value occurs simultaneously with one of said pulses, and the amplitude of said derived voltage over said major portion of said period being such that said diode is maintained nonconductive even in the presence of a pulse of an amplitude comparable with that of said pulses.

8. A periodic wave generator adapted to be excited by periodic voltage pulses comprising, a vacuum-tube oscillator having a pulse-responsive input circuit and an output circuit, a diode effectively in series in said input circuit and responsive to said voltage pulses for coupling into said input circuit corresponding current pulses, impedance means in said input circuit for developing a pulse voltage in said input circuit in response to said current pulses to synchronize said oscillator, means for deriving from said output circuit a periodic voltage having a substantially different value at a predetermined point at each period than over the major portion of said period and for applying said voltage to said input circuit for regeneration of said oscillator, and means for applying said derived voltage as a bias to said diode with such polarity that it is biased in opposition to conduction to a lesser degree at said predetermined point of each period than over said major portion of each period, said pulses being applied to said diode with such polarity as to tend to render said diode conductive, the amplitude of said voltage of substantially different value being such that said diode is rendered conductive if such value occurs simultaneously with one of said pulses, and the amplitude of said voltage over said major portion of said period being such that said diode is maintained nonconductive even in the presence of a pulse of an amplitude comparable with that of said pulses.

9. A periodic wave generator adapted to be excited by periodic voltage pulses comprising a

vacuum-tube oscillator having a pulse-responsive input circuit and an output circuit, a diode effectively in series in said input circuit and responsive to said voltage pulses for coupling into said input circuit corresponding current pulses, a resistor in said input circuit for developing a pulse voltage in said input circuit in response to said current pulses to synchronize said oscillator, means for deriving from said output circuit a periodic voltage having a substantially different value at a predetermined point at each period than over the major portion of said period and for applying said voltage to said input circuit for feedback in said oscillator, and means for applying said derived voltage as a bias to said diode with such polarity that it is biased in opposition to conduction to a lesser degree at said predetermined point of each period than over said major portion of each period, said pulses being applied to said diode with such polarity as to tend to render said diode conductive, the amplitude of said voltage of substantially different value being such that said diode is rendered conductive if such value occurs simultaneously with one of said pulses, and the amplitude of said voltage over said major portion of said period being such that said diode is maintained nonconductive even in the presence of a pulse of an amplitude comparable with that of said pulses.

10. A saw-tooth wave generator adapted to be synchronized by periodic voltage pulses comprising, a vacuum-tube oscillator having a pulse-responsive input circuit, a diode effectively in series in said input circuit and responsive to said voltage pulses for coupling into said input circuit corresponding current pulses, a feed-back circuit for said vacuum tube comprising a condenser in said input circuit and a resistor for deriving across said condenser a periodic voltage having a substantially different value at a predetermined point of each period than over the major portion of said period, a resistor in series with said first-mentioned condenser included in said input circuit for developing voltage pulses in response to said current pulses, and means for applying said derived voltage as a bias to said diode with such polarity that it is biased in opposition to conduction to a lesser degree at said predetermined point of each period than over said major portion of each period, said pulses being applied to said diode with such polarity as to tend to render said diode conductive, the amplitude of said voltage of substantially different value being such that said diode is rendered conductive if such value occurs simultaneously with one of said pulses and the amplitude of said voltage over said major portion of said period being such that said diode is maintained nonconductive even in the presence of a pulse of an amplitude comparable with that of said pulses.
